UNITED STATES PATENT OFFICE.

LEWIS G. McCLINTOCK, OF PITTSBURGH, PENNSYLVANIA, ASSIGNEE TO PITTSBURGH TRANSFORMER COMPANY, A CORPORATION OF PENNSYLVANIA.

TRANSFORMER-TANK SUPPORT.

Application filed December 9, 1921. Serial No. 521,210.

To all whom it may concern:

Be it known that I, LEWIS G. McCLINTOCK, a citizen of the United States, residing at Pittsburgh, in the county of Allegheny and State of Pennsylvania, have invented certain new and useful Improvements in Transformer-Tank Supports, of which the following is a specification.

This invention relates to supporting means for tanks and particularly to a support for a transformer tank containing a transformer submerged in oil. The object of the invention is to provide a means whereby a transformer adapted for platform support may readily be mounted on a pole in elevated position.

In the accompanying drawings illustrating the invention—

Fig. 1 is an elevational side view of a transformer tank support and

Fig. 2 is a plan view of the same with parts broken away.

In the specific embodiment shown in the drawings a support is shown adapted for holding a large size transformer tank T indicated in outline by broken lines. The support comprises a base B with front and rear angle bars 5 and 6 and transverse channels 7 with their webs connected to the inner vertical flanges of the angle bars by angle cleats 8. The base B thus prevents a grid-like structure with a flat upper surface upon which sits the transformer tank T.

The rear angle 6 at each end carries rearwardly extending hook members 10 passing in bent form from beneath the horizontal flange of the angle and fastened thereto in any suitable manner. Side straps 11 extend at an incline from each end of the front angle 5 and are bent at their upper ends to form the upper hooks 12, while vertical side braces 14 are connected between these side straps and the rear angle 6. Fastened to these vertical braces is the hoop strap 15 extending around the body of the transformer tank T and holding it securely in place on the base B.

The upper frame work provided by the straps 11 and braces 14 at each side evenly supports the base and permits the whole structure with its tank T to be suspended from horizontal beams such as b, b'. The

tank T is securely supported by the rigid base and hoop strap 15 and at the same time the top of the transformer is left free of encumbrance and clear for the attachment of the lead wires, etc. Instead of being suspended in elevated position by the hooks 10, 12 the base B may be set directly on the ground or floor and the tank T resting on the base will be held in position by the frame structure above.

I claim:—

1. A support for a transformer tank comprising a flat base, and side frames of stock material cut to length and fastened rigidly together and to the base and formed with hook means for suspending said base, and a retaining strap member fastened between said side frames and adapted to surround the transformer tank below the cover, said base and side frames forming a unitary removable support adapted to hold a transformer tank and permit its vertical removal from said support.

2. A support for a transformer tank comprising a flat base projecting outward from the line of support, and means for thus suspending said base comprising a pair of inclined side members hooked at their upper ends and other side members connected between said inclined members and said base in a rigid side frame formation, said side members and base forming a unitary removable support, and a retaining strap extending between said side frames and adapted to surround the transformer tank and hold it in place on said base and permit its vertical removal from said support.

3. A support for a transformer tank comprising a flat base composed of front and rear and transverse members in a unitary grid-like formation, means for suspending said base comprising a pair of inclined side straps hooked at their upper ends and attached to said base at their lower ends, other strap members connected between said inclined side straps and said base, and means for retaining the transformer tank in place on said base, the whole forming a unitary removable support adapted to hold a transformer tank and permit its removal.

LEWIS G. McCLINTOCK.
